HANGING FOUNTAIN LAMP

Marvin A. Mackey, 10818 NE. 117th Ave.,
Vancouver, Wash. 98662

Filed Jan. 28, 1971, Ser. No. 110,790

Term of patent 14 years

Int. Cl. D26—05

U.S. Cl. D48—23

FIG. 1

FIG. 2

FIG. 3

MARVIN

FIG. 1 is a front view of a hanging fountain lamp in accordance with my new design;

FIG. 2 is a top view thereof;

FIG. 3 is a bottom view thereof; and

FIG. 4 is a cross-sectional view taken on a horizontal plane through the center of FIG. 1 at 4—4.

The chain is broken away to indicate indeterminate length.

I claim:

The ornamental design for a hanging fountain lamp, as shown and described.
